Primary Examiner—Cathron B. Matta*Attorney, Agent, or Firm*—Michael McGreal**[57]****CLAIM**

The ornamental design for a figurine attached to the dip tube of a container, as shown and described.

DESCRIPTION

FIG. 1 is a perspective view of the figurine attached to the dip tube of a container of my design attached to a dip tube of a container.

FIG. 2 is a left side elevation view thereof.

FIG. 3 is a right side elevation view thereof.

FIG. 4 is a top plan view thereof.

FIG. 5 is a bottom plan view thereof.

FIG. 6 is a front elevation view thereof; and, FIG. 7 is a back elevation view thereof.

The broken line showing of a container and pump is for illustrative purposes only and forms no part of the claimed design.
